CLAIM

The ornamental design for an umbrella mount, as shown and described.

DESCRIPTION

FIG. 1 is a perspective view of an umbrella mount;

FIG. 2 is a front elevation view thereof;

FIG. 3 is a right side elevation view thereof;

FIG. 4 is a left side elevation view thereof;

FIG. 5 is a top view thereof;

FIG. 6 is a rear elevation view thereof; and,

FIG. 7 is a bottom view thereof.

The broken lines shown in FIGS. 1-7 are included to the purpose of illustrating environmental elements only and form no part of the claimed design.
